CONTAINER CAPPING DEVICE

Thomas A. Nelson, Chicago, Ill.

Application September 16, 1944, Serial No. 554,381

1 Claim. (Cl. 226—83)

1

My invention relates to an improvement in container capping device.

It is well known that container capping devices of conventional design are relatively slow in operation, complicated and unwieldy, having many moving and integrated parts, and that same are costly to make and to operate, and require the attendance of many and highly skilled workmen to operate. It is also well known that due to the complicated design of the conventional container capping machines, breakdowns of said machines often occur, and repair and replacement of various parts is required frequently. It is also well known that in the operation of conventional machines a comparatively high rate of breakage of containers occurs during the capping process. These conditions increase the cost of capping and decrease the production of capped containers.

It is further well known that container capping machines of conventional design are somewhat hazardous to operate both from the standpoint of the operation of the machines themselves and also because of container breakage, and consequently a container capping device which would lessen this hazard would be very desirable both from the manufacturers' and operators' standpoints.

One object of my invention is to provide an improved, efficient, fast and reliable container capping device of simple construction and operation.

Another object is to provide a container capping machine inexpensive to produce and which would require the service of fewer and less skilled operators than is required with conventional capping devices.

A further object of my invention is to provide an improved container capping device which will be safer to operate and cause a decreased amount of breakage of containers being capped.

Other objects and advantages will appear as my invention is hereinafter developed.

In one embodiment of my invention, a punch press of the usual construction, comprising a stand with a bed affixed to it and having a punch slide capable of descending or ascending at the will of the operator positioned over said bed, is provided with a capping device consisting of three main units, viz., a cylindrical housing having a hollow stem extending therefrom which is adapted to be fitted into and affixed to the reciprocating member of the punch press; a piston having an aperture in the center of its head is fitted freely into the cylindrical interior of the

2

housing and fastened thereto by springs and guides so as to allow freedom of movement of said piston in a line parallel and concentric with the axis of the cylindrical housing. The housing is vented to prevent entrapment of air between the piston head and the cylinder head of the housing. Piston has tapered internal walls, the taper being such that the internal diameter of the piston is smaller at the piston head than it is at its lower extremity. A plunger is mounted within the piston with the stem extending through the piston head and into the hollow stem of the housing. This plunger is spring-mounted to the housing by the insertion of a coil spring within the hollow stem of the housing in such a manner as to encircle the plunger stem and allow free relative movement between said parts so that the plunger may move in a line parallel to and concentric with the axis of the cylindrical housing and piston.

There are many other possible arrangements and shapes of these three main units, as the housing, piston and plunger do not have to be cylindrical but could be elliptical, square, or any other shape, and such is the contemplation of this invention. Likewise, the plunger does not necessarily have to have a stem extending therefrom but could instead be simply a disc spring mounted to the piston in which it operates. Also, the piston head in this case would not then have an aperture for the allowance of the introduction of the plunger stem therethrough. Also, the cylindrical walls of the housing could be eliminated and still have this mechanism operated properly, and that is the contemplation of this invention, it being clearly understood that the embodiment herein described is simply a preferred form of mechanism and not the only form that is workable.

A more complete understanding of my invention may be had from the following complete description in conjunction with the appended drawings, in which:

Figure 1 is a side elevation of the complete container capping device including a motor-operated punch press, a capping unit, the container, the container cap and the container guide.

Figure 2 is a detailed elevation of the capping unit in which a cutaway view disclosing the cross-sectional details is shown.

Figure 3 is a plan view of this capping unit.

Figure 4 is a fragmentary detailed cross-sectional view showing the condition of the cap edge before bending into gripping contact with the annular bead on the container; and

Figure 5 is the same approximate view as Figure 4 after the bending unit of the capping mechanism has bent the cap flange into gripping contact with the annular bead on the container.

My preferred form of improvement in container capping device comprises a conventional punch press made up of a rigid stand 31, a punch press bed 32, affixed to said stand, a punch slide 38, guided by slide guide 41, affixed to the stand by bolts 42, and connected to crank shaft 51 through connecting rod 44, from bearing 43 in the punch slide to bearing 45 in the crank shaft, said crank shaft being rotated by movement of flywheel 55 through reduction gears. Flywheel 55 being rotated by electric motor 56 through pulley 57 connected to motor shaft 58. Power from said motor being transmitted to the flywheel from the motor by means of belt 54 connecting motor pulley 57 and flywheel pulley 53, the motor being anchored to standard 59 through its base 60. The stamping reaction being transmitted through the capping device to the punch press slide 38 and through the train of shafts and bearings to the punch press stand 37 through the beam action of beam 52.

Inserted in the punch press slide 38 and affixed thereto is the capping device, said capping device consisting of a cylindrical housing 11 having a hollow stem 10 extending therefrom. A piston 12 is mounted to said cylindrical housing by means of bolts 20 and springs 21, said springs being inserted in indentations 22 in the housing and indentations 23 in the piston head, the bolts 20 acting as guides to allow the piston to move in a line parallel to the axis of the housing and concentric with same. The springs 21 under compression force the piston head away from the cylinder head of the housing but allow this gap to be closed upon proper relative pressure being brought to force the piston head into closer conjunction with the cylinder head of the housing. In order to avoid entrapment of air in the space included between the piston head and the cylinder head of the housing, vents 25 have been introduced into the housing. The interior walls 24 of the piston 12 are tapered so that the internal diameter of the piston at its head is smaller than the internal diameter of the piston at its lower edge.

A plunger 13, having a stem 14 extending therefrom is inserted into the interior of the piston so that plunger stem 14 extends through the aperture 26 in the piston head. Said plunger stem further extends through the hollow stem 10 of the housing. The diameter of the plunger stem 14 is enough smaller than the internal diameter of the hollow stem 10 of the housing to allow the introduction of compression spring 15 in such a manner as to encircle plunger stem 14 and tend to force the plunger 13 downward until stop nut 17, secured in place by lock nut 18, comes into contact with the upper surface of the housing 16, which said stop nut 17 determines the maximum thrust downward of the plunger 13. Expansion and impact strains in the housing are taken up through the circular groove 27 cut into the cylindrical housing at the base of the housing stem. A container 29 having a cap 28 covering the opening in same and extending beyond said opening, and having an annular bead 30 affixed to or monolithic with the exterior edge of its opening is placed on bed 32 against guide 34 which in turn is bolted to bed 32 by bolts 36 through shaft 33. This guide has adjustable slots through which the bolts 36 extend in order to allow adjustment in

placing. Plunger 13 descends upon cap 28 and holds it firmly in place on container 29 over the opening in said container, the outer flange 31 extending beyond the annular bead 30 and being reinforced by serrations 61. Piston 12 having internally tapered wall 24, upon further descent presses flange 31, serrations 61 and cap edge indentations 62 into gripping contact with annular bead 30 permanently fastening cap 28 to container 29.

Upon ascent of punch press slide 38 the capping unit is withdrawn from contact with the cap and container, said capped container then being left free for removal from the machine.

Other modifications and adaptations of the above disclosures are contemplated, and it is understood that my invention is limited only by the scope of the appended claim.

I claim:

In combination, a container capping press comprising a stand, a reciprocating member mounted on said stand, means for causing the reciprocating member to descend and rise, a bed mounted below said reciprocating member, and guide affixed to said bed effective to determine the proper placing of a container thereon for capping, and a capping device comprising a stemmed base member, the upper portion of which is a hollow cylindrical stem of relatively small diameter adapted to be affixed to the reciprocating member and the lower portion of which is a hollow cylinder of a large diameter fixedly attached to the stemmed portion and having vent and guide holes in the head of the lower cylinder, a hollow cylindrical piston-like cap bending member fitted within the lower cylinder of the base member having vertical exterior walls and tapered internal walls and having an opening in the center of its head, said cap bending member being flexibly mounted to the base member and guided by the contact of its exterior walls with the interior walls of the base member so as to be movable only in a line parallel to the axis of the stem of the base member, rigid protuberances affixed to the head of the cap bending member and extending upwardly therefrom into and through the guide holes in the base member effective to mechanically stabilize the limiting of the movement of the cap bending member to a direction parallel with the vertical axis of the stem of the base member and control said movement so as to prevent descent of the cap bending member beyond a predetermined position, and a stemmed plunger spring mounted within the base member by extension of the stem upwardly through the center hole in the cap bending member and into and through the hollow stem of the base member effective to limit the movement of the plunger to a line parallel with the vertical axis of the stem of the base member and prevent its descent beyond a predetermined position, the foregoing capping device being effective, upon descent of the reciprocating member, to cause the plunger to descend upon and hold a cap firmly in place on a container over its opening without causing excessive pressure on such cap and upon further descent of the reciprocating member to cause the cap bending member to descend on that portion of the cap extending over the periphery of the container opening, and bend it down and into gripping contact with the container so as to affix such cap to such container but to prevent descent of said cap bending member beyond a point where damage would be caused to such container and upon ascent of

the reciprocating member to release such capped container for removal from the capping device.
